UNITED STATES PATENT OFFICE.

FRANK W. COREY, OF MOBRIDGE, SOUTH DAKOTA.

FILLING APPARATUS.

Application filed April 23, 1925. Serial No. 25,336.

This invention relates to certain improvements in filling apparatus and has relation more particularly to a device of this general character especially designed and adapted for use in filling salt and pepper shakers, and it is an object of the invention to provide a device of this kind with means whereby it is assured the salt before being delivered is in a comminuted state.

It is also an object of the invention to provide a device of this kind wherein the pepper before being discharged or delivered is effectively screened to prevent clogging of the valve for controlling the discharge of the pepper.

The invention consists in the details of construction and in the combination and arrangement of the several parts of my improved filling apparatus whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation illustrating a filling apparatus constructed in accordance with an embodiment of my invention;

Figure 2 is a sectional view taken substantially on the line 2—2 of Figure 1;

Figure 3 is a sectional view taken substantially on the line 3—3 of Figure 1;

Figure 4 is an enlarged fragmentary vertical sectional view illustrating in detail the lifting member, the crushing member and conveyor;

Figure 5 is a fragmentary view in section taken through the discharge spout for the pepper compartment.

As disclosed in the accompanying drawings, C denotes a container of requisite dimensions and divided by an intermediate vertically disposed partition 1 into the compartments A and B the tops of each of such compartments being provided with a lid 2 whereby the same may receive the requisite supply of condiment. The front wall of each of the compartments A and B is also provided with a transparent window 3 so that visual access may be had therein.

The compartment A is particularly adapted to contain a supply of pepper and the bottom wall 4 thereof is disposed on an incline toward the depending discharge spout 5, flow through said spout being under control of the rotary valve 6 operated by the thumb wheel 7. The valve 6 is normally maintained in a closed position by the coil spring 8 surrounding the extended portion of the valve member 6 and having one extremity secured to the thumb wheel 7 and its opposite end portion to the adjacent wall of the spout 5. When the valve 6 is turned into open position, the spring 8 is placed under increased tension sufficient to automatically turn or rotate the valve member 6 to close the discharge through the spout 5 when the thumb wheel 7 is released.

The bottom wall 9 of the compartment B is also disposed on a downward incline and discharges within the trough 10 extending lengthwise of the front of the compartment B, said trough being substantially semi-circular in cross section. In communication with the inner end portion of the trough 10 and depending from the bottom wall of the compartment is a discharge spout 11. The trough 10 extends across the upper or receiving end of the spout 11 but said extended portion 10' terminates a slight distance from the front wall of the compartment B, said portion of the compartment being enlarged, as at 12, whereby the passageway 14 is provided to afford communication between the inner end of the trough 10 and the discharge spout 11. The trough 10 is arranged within a lower forward extended portion 15 of the compartment B and arranged immediately adjacent the inner end of said extended portion 15 is a housing 16 with which the passageway 14 communicates. The extended portion 10' of the trough constitutes the bottom of said housing 16.

Disposed lengthwise of the housing and rotatably supported by the end walls of the lower extended portion 15 is a shaft 17, the portion of the shaft disposed through the housing 16 having fixed thereto the fan or paddle wheel 18 which, upon requisite rotation of the shaft 17, causes the salt received within the housing to be carried upwardly and discharged through the passageway 14 through the spout 11.

Within the housing 16 to the inner side of the fan or paddle wheel 18 is a grinder wheel or burr 19 fixed to the shaft 17 for ro-

tation therewith but having movement lengthwise of the shaft. The grinder wheel or member is constantly urged toward the inner side of the housing 16 by the coil 5 spring 20 encircling the shaft and interposed between said grinder member or wheel and the applied fan or paddle wheel 18.

The portion of the shaft 17 outwardly of 10 the housing 16 carries a spiral conveyor 21 working within the trough 10 so that as the shaft 17 is rotated the salt within the compartment B will be forced into contact with the grinder wheel or burr 19 so that any 15 lump or caked salt will be effectively comminuted before the salt is discharged by the action of the fan or wheel 18 to the discharge spout 11.

As herein disclosed, the grinder wheel or 20 burr 19 is cup-shaped with its open end disposed in a direction toward the fan or wheel 18 and said grinder element or burr is gradually tapered from its open end toward its 25 closed end as is clearly illustrated in the accompanying drawings.

The shaft 17 extends exteriorly of the outer end wall of the compartment B and to 30 said extended portion is fixed an operating handle 22 although it is to be understood that any suitable means may be employed to effect the desired rotation of the shaft.

The compartment A is intersected by the horizontally disposed sieve or screen element 23 which serves to prevent any foreign 35 particles in the pepper clogging or stopping the valve member 6.

From the foregoing description it is 40 thought to be obvious that a filling apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein 45 shown in carrying out my invention in practice except as hereinafter claimed.

I claim:—

1. An apparatus of the class described 50 comprising a compartment having a discharge spout in communication therewith, the discharge spout being in communication with the compartment at a point above the low point of such compartment, means for lifting the material in such compartment 55 for discharge through such spout, and a crushing element adjacent said lifting means.

2. An apparatus of the class described 60 comprising a compartment having a discharge spout in communication therewith,

the discharge spout being in communication with the compartment at a point above the low point of such compartment, means for lifting the material in such compartment for discharge through such spout, a crushing element adjacent said lifting means, and means for conveying material to the crushing element and lifting means. 70

3. An apparatus of the class described comprising a compartment having a discharge spout in communication therewith, the discharge spout being in communication with the compartment at a point above the low point of such compartment, means for lifting the material in such compartment 80 for discharge through such spout, a crushing element adjacent said lifting means, means for conveying material to the crushing element and lifting means, and a common operating medium for the lifting 85 means, crushing element and the conveying means.

4. An apparatus of the class described comprising a compartment having a discharge spout in communication therewith, 90 a trough within the lower portion of the compartment and extending above the spout, the upper portion of the trough at one side thereof being in communication with the spout, the spout being entirely below the trough, a shaft disposed through the compartment and supported by opposite walls thereof, said shaft being positioned above the trough, a rotary lifting member mounted on the shaft above the spout for discharging 95 material into the spout.

5. An apparatus of the class described comprising a compartment having a discharge spout in communication therewith, a trough within the lower portion of the compartment and extending through the spout, the upper portion of the trough at one side thereof being in communication with the spout, a shaft disposed through the compartment and supported by opposite walls 105 thereof, said shaft being positioned above the trough, a rotary lifting member mounted on the shaft above the spout for discharging material into the spout, and a crushing element mounted on the shaft adjacent to the 110 lifting member.

6. An apparatus of the class described comprising a compartment having a discharge spout in communication therewith, a trough within the lower portion of the compartment and extending through the spout, the upper portion of the trough at one side thereof being in communication with the spout, a shaft disposed through the compartment and supported by opposite walls 120 thereof, said shaft being positioned above the trough, a rotary lifting member mounted on the shaft above the spout for discharging material into the spout, a crushing member mounted on the shaft adjacent to 125 130

the lifting member, said crushing member being freely movable lengthwise of the shaft, and an expansible member interposed between the lifting member and the crushing member.

7. An apparatus of the class described comprising a compartment having a discharge spout in communication therewith, a trough within the lower portion of the compartment and extending through the spout, the upper portion of the trough at one side thereof being in communication with the spout, a shaft disposed through the

compartment and supported by opposite walls thereof, said shaft being positioned above the trough, a rotary lifting member mounted on the shaft above the spout for discharging material into the spout, a crushing member mounted on the shaft adjacent to the lifting member, and a spiral conveyor carried by the shaft in advance of the crushing element and working in the trough. 15 20

In testimony whereof I hereunto affix my signature.

FRANK W. COREY.
